CLAIM

An ornamental design for a light fixture, as shown.

DESCRIPTION

FIG. 1 is a perspective view of a light fixture;
FIG. 2 is another perspective view of the light fixture of FIG. 1 thereof;
FIG. 3 is a front view of the light fixture of FIG. 1 thereof;
FIG. 4 is a rear view of the light fixture of FIG. 1 thereof;
FIG. 5 is a left side view of the light fixture of FIG. 1 thereof;
FIG. 6 is a right side view of the light fixture of FIG. 1 thereof;
FIG. 7 is a top view of the light fixture of FIG. 1 thereof; and,
FIG. 8 is a bottom view of the light fixture of FIG. 1 thereof.
The broken lines shown in FIGS. 1-8 illustrate portions of
the light fixture that form no part of the claimed design.
